UNITED STATES PATENT OFFICE.

SIDNEY M. HARVEY AND SAMUEL E. LORENZ, OF DETROIT, MICHIGAN, ASSIGNEES TO ELECTRIC WELDING MACHINE COMPANY, OF DETROIT, MICHIGAN, A COPARTNERSHIP FIRM.

DESIGN FOR AN ELECTRIC-TRANSFORMER CASE.

55,422.

Specification for Design.

Patented June 8, 1920.

Application filed November 19, 1919. Serial No. 339,197. Term of patent 14 years.

To all whom it may concern:

Be it known that we, SIDNEY M. HARVEY and SAMUEL E. LORENZ, citizens, respectively, of the Dominion of Canada and the United States of America, residing at Detroit, in the county of Wayne and State of Michigan, have invented a new, original, and ornamental Design for an Electric-Transformer Case, of which the following is a specification, reference being had to the accompanying drawing, forming part thereof.

In the accompanying drawing—

Figure 1 is a perspective view of a cabinet embodying our design.

Fig. 2 is an end elevation.

Fig. 3 is a top plan of the design as shown in Fig. 1.

We claim:

The ornamental design for an electric transformer case as shown.

SIDNEY M. HARVEY.

SAMUEL E. LORENZ.

Signed in the presence of—

B. F. WHEELER,

M. E. BROESAMLE.
